US00D574337S

(12) **United States Design Patent**
Panaccione et al.

(10) **Patent No.:** **US D574,337 S**
(45) **Date of Patent:** **** Aug. 5, 2008**

(54) **LED PACKAGE**

(75) Inventors: **Paul Panaccione**, Newburyport, MA (US); **Christian Hoepfner**, North Andover, MA (US); **Georgia Chmielewski**, Plaistow, NH (US)

(73) Assignee: **Luminus Devices, Inc.**, Billerica, MA (US)

(**) Term: **14 Years**

(21) Appl. No.: **29/285,459**

(22) Filed: **Mar. 29, 2007**

(51) **LOC (8) Cl.** **13-03**

(52) **U.S. Cl.** **D13/180**

(58) **Field of Classification Search** D13/180; D26/2; 257/79, 80, 81, 88, 89, 95, 98, 99, 257/100; 313/483, 498, 500; 362/555, 800

See application file for complete search history.
